ATTORNEY

UNITED STATES PATENT OFFICE.

WILLIAM D. KENNEDY, OF OAKLAND, CALIFORNIA, ASSIGNOR OF ONE-HALF TO
GEORGE L. WALLACE, OF OAKLAND, CALIFORNIA.

CLAMP.

1,154,405.

Specification of Letters Patent. Patented Sept. 21, 1915.

Application filed March 29, 1915. Serial No. 17,831.

To all whom it may concern:

Be it known that I, WILLIAM D. KENNEDY, a citizen of the United States, residing at Oakland, in the county of Alameda and 5 State of California, have invented new and useful Improvements in Clamps, of which the following is a specification.

This invention relates to a clamp.

One of the objects of the present invention is to provide a clamp which may be 10 used for various purposes, such as a tug or trace fastener, wire stretcher, coupler, etc.

Another object of the invention is to provide a device of the character described, 15 which is simple, substantial and cheap to manufacture, and which may be quickly applied or detached, as the case may be.

Further objects will hereinafter appear.

The invention consists of the parts and 20 the construction and combination of parts as hereinafter more fully described and claimed, having reference to the accompanying drawings, in which—

Figure 1 is a perspective view of the 25 clamp. Fig. 2 is a sectional elevation.

A indicates a metal clip or clamp consisting of a pair of connected angularly disposed spring arms 2 which are slotted, as indicated at 3. Mounted between the 30 arms is a pair of wedge-shaped gripping members 4, on the inner faces of which are formed corrugations or teeth 5. The wedges or gripping members are slidable and are thus adapted to compress and grip the 35 leather tug 6, or other article, to which they are applied.

The wedges are mounted independently 40 of each other and carry buttons 7 which project through the slots 3 formed in the arms of the clamp. The wedges are in this manner guided in their sliding movement and are, furthermore, prevented from dropping out.

Surrounding the arms 2 and coöperating 45 with same to force the teeth on the jaws into the tug to grip and hold the leather is a clamping ring 8. The ring is slidably mounted on the arms and is, therefore, adjustable on same to coöperate with the jaws 50 in any position.

A clamp constructed as here shown may

be used for various purposes. In Fig. 1 it is shown as a tug or trace fastener. In this instance a snap hook of suitable construction may be attached to same, as indicated at 9. It may also be used as a wire stretcher, rod coupler, or the like. In this instance the snap hook may be eliminated, as indicated in Fig. 2, to permit the wire or rod to pass through, as indicated at 10. 60

The clamp is simple and substantial in construction and may be quickly released, as it is only necessary to force the clamping ring in a downward direction and the wedges in an upward direction. The flexible structure of the spring arms, together with the adjustable wedges, permits straps, rods, wires, and the like of varying thickness to be handled, thus permitting a standard clamp to be used at all times. 70

The materials and finish of the several parts of the device are such as the experience and judgment of the manufacturer may dictate.

I wish it understood that various changes 75 in form, proportions, and minor details of construction may be resorted to within the scope of the appended claims and that I do not wish to limit myself to the specific design and construction here shown. 80

Having thus described my invention, what I claim and desire to secure by Letters Patent is—

1. A clamp including a U-shaped member, a clamping member encircling the arms of 85 said member, each of the arms being longitudinally slotted, a pair of wedge-shaped gripping members between the arms, and means on the gripping members engaged in the slots to guide the members, said clamping member extending over the side edges of the members so as to coact with the guiding means to prevent lateral movement of the gripping members. 90

2. A clamp including a U-shaped member, 95 a clamping member encircling the arms of said member, each of the arms being longitudinally slotted, a pair of wedge-shaped gripping members between the arms, and means on the gripping members engaged in 100 the slots to guide the members, said clamping member extending over the side edges of

the members so as to coact with the guiding means to prevent lateral movement of the gripping members, the free ends of the U-shaped member being turned outwardly so
5 as to restrict movement of the clamping member in one direction.

In testimony whereof I have hereunto set

my hand in the presence of two subscribing witnesses.

WILLIAM D. KENNEDY.
